CLAIM

The ornamental design for a control head for a mobile radio, as shown and described.

DESCRIPTION

FIG. 1 is a front elevational view of a control head for a mobile radio in accordance with our new design;

FIG. 2 is a top plan view thereof;

FIG. 3 is a bottom plan view thereof;

FIG. 4 is a left side elevational view thereof;

FIG. 5 is a right side elevational view thereof; and,

FIG. 6 is a front, top, and right side isometric view thereof. The back of the control head for a mobile radio forms no part of the claimed design.
